UNITED STATES PATENT OFFICE.

JOHN V. RUND, OF PESOTUM, ILLINOIS.

SAFETY-STOP FOR TRAINS.

Specification of Letters Patent.

Patented Jan. 18, 1916.

1,168,337.

Application filed February 20, 1915. Serial No. 9,671.

To all whom it may concern:

Be it known that I, JOHN V. RUND, a citizen of the United States, residing at Pesotum, in the county of Champaign and State of Illinois, have invented certain new and useful Improvements in Safety-Stops for Trains, of which the following is a specification.

My present invention relates to new and useful improvements in safety appliances for railways and more particularly to that class of safety appliances intended to prevent an engineer running a train past a danger signal, the primary object of my invention being the provision of means upon a locomotive, engageable by a track obstacle for successively closing the throttle valve of the locomotive and applying the air brakes of the train.

My improved safety appliance is intended to operate in connection with track obstacles which may be thrown in or out of active position and one object of my invention consists in the provision of a novel form of actuating member engageable with a track obstacle when the latter is in active position, to operate through a cable or other suitable connection to open a vent valve included in the train pipe or a branch thereof.

A still further object of my invention consists in the provision of a novel form of vent valve, of the turn plug type, the valve being so arranged as to discharge train pipe air into a throttle valve closing mechanism to actuate such mechanism, the air thus discharged subsequently escaping from the mechanism to vent the train pipe.

A still further object of my invention is to so arrange the throttle valve closing mechanism that the throttle valve may be manually manipulated in the usual manner without opening the vent valve referred to.

A still further object of my invention consists in providing means, whereby manual closing of the throttle valve will render the vent valve inoperative and thus prevent application of the brakes, even though a track obstacle is passed.

In this connection, a still further object of my invention consists in providing a vent valve of the turn plug type having a clutch head rotatable by the track obstacle actuated mechanism to open the valve and further having a clutch releasing member operable by the throttle valve to disengage the clutch

from the valve stem and, therefore, prevent opening of the valve by engagement of the trip actuated mechanism with a trip.

In this connection, a still further object of my invention consists in so constructing and arranging the clutch head and clutch releasing member that they will be automatically returned to normal position, when released, although the valve will still remain in open position.

For this reason, a still further object of my invention consists in means for manually closing the valve.

With these and other objects in view, my invention will be more fully described, illustrated in the accompanying drawings, then specifically pointed out in the claims which are attached to and form a part of this application.

In the drawings: Figure 1 is a fragmentary side elevation of a conventional locomotive, showing my safety appliance applied thereto and also showing one of the track obstacles in active position; Fig. 2 is a central, longitudinal sectional view of the vent valve which I employ; Fig. 3 is a transverse sectional view taken on the line 3-3 of Fig. 2, looking in the direction of the arrows; Fig. 4 is a similar view on the line 4-4 of Fig. 2, looking in the direction of the arrows; Fig. 5 is a similar view taken on the line 5-5 of Fig. 2, looking in the direction of the arrows; Fig. 6 is a perspective view of one part of the clutch releasing member; Fig. 7 is a similar view of the other part of the clutch releasing member.

Corresponding and like parts are referred to in the following description and indicated in all the views of the drawings by the same reference characters.

The vent valve, its construction, and manner of operation, must be understood to permit appreciation of the operation of my safety appliance as a whole and for this reason I will describe such valve, which is indicated as a whole by the numeral 10, before describing the rest of the appliance. This valve includes a substantially cylindrical valve casing 11, enlarged at one end to provide diametrically extending attaching ears 12 to receive bolts or other suitable fastening devices 13 by which it may be secured to the locomotive at any suitable point, preferably to the jacketing of the boiler to extend at right angles thereto.

95

105

110

The opposite end of the valve casing 11 is reduced as shown at 14 in Fig. 2, and the entire valve casing is provided with a central longitudinal bore 15. This bore, which is uniform in diameter through the reduced portion of the valve casing, gradually increases in diameter from such portion, as shown, to provide a frusto-conical valve seat 16, while the opposite end of the casing is counterbored to provide a cylindrical chamber 17 in axial alignment with and forming a continuation of the bore and valve seat, the meeting of the chamber and valve seat providing the inclined, circumferential stop shoulder 18. The wall of the chamber, at its outer end, is threaded as at 19 to receive an adjustable plug 20 having a spring centering extension 21 at its inner end.

Seated in the valve seat 16, is a frusto-conical valve 22 of the turn plug type provided with a diametrically formed transverse fluid passage 23 which, in one position, establishes communication between the inlet and outlet passages 24 and 25 formed in the body 26 of the valve casing and in another position cuts off such communication. The outer end of the body of the valve 22 is formed with a stop shoulder 26 to seat against the shoulder 18 and a helical spring 27 is interposed between the plug 20 and end of the valve to hold the valve closely in its seat, the tension of the spring being adjusted by the plug 20 and the spring being maintained in central position by the portion 21 of such plug. The valve 22 is provided, being preferably formed integral with a cylindrical valve stem 28 which fits closely within the bore 15 of the valve casing and at its free end extends a considerable distance beyond the reduced end of the casing, having a reduced terminal 29 to engage in the socket 30 of the hub of a hand wheel 31, this extension and socket being square in order that turning of the hand wheel may turn the valve stem. A screw 32 prevents displacement of the hand wheel from the valve stem, and the hub portion of the hand wheel, as shown, is greater in diameter than the greatest diameter of the valve stem in order to provide an annular shoulder 33.

Surrounding the free end of the valve stem and engaging against the adjacent end of the valve casing, is a substantially cylindrical clutch head 34, the valve stem receiving bore of which is enlarged at its outer end to form an annular chamber 35 to receive a helical spring 36 which engages the shoulder 33 of the hand wheel and an internal shoulder 37 of the clutch head to normally hold the clutch head in engagement with the free end of the valve casing, as shown in Fig. 2. The opposite or inner end of the clutch head is provided with an annular flange or sleeve 38 which surrounds but is spaced from the free end portion of the valve casing 14, ter-

minating considerably short of the annular shoulder 39 formed by reducing the valve casing and thereby providing an annular chamber about the free end of the valve casing. The body of the clutch head 34, as best shown in Figs. 2 and 3 of the drawings, is provided with a radially directed extension 40 formed with a circumferential slot 41, the inner wall of which is, in effect, tangential to the main body of the clutch head, this slot being adapted to receive one end portion of a lever 42 which is pivoted as shown at 43 in the extreme end portion of the extension and which projects tangentially with respect to the clutch head, being provided at its free end, which extends beyond the clutch head, with a pivot pin receiving opening 44. This slotted extension is formed upon the upper face of the clutch head and it will therefore be clear that downward pulling upon the free end of the lever 42 will serve to partially rotate the clutch head with respect to the valve casing, or the valve stem unless such stem turns with the head.

The valve stem is formed with a diametric slot 45 to receive the inner ends of projectable keys 46 which are normally held in projected position by a helical spring 47 seated in the intermediate portion of the slot and engaging the inner ends of the keys. The outer ends of the keys are oppositely beveled so that such ends, which normally seat in diametrically formed longitudinal keyways 48 in the clutch head, have their outer faces in planes substantially tangential to the valve stem to co-act with the corresponding side walls of the keyways, said walls being also tangential to the valve stem. Because of this, turning of the clutch head in one direction will act through the keys to turn the stem, while turning of the clutch head in the opposite direction will merely force the keys into the slot of the shaft and so have no turning effect on the valve stem.

Mounted upon the reduced portion 14 of the valve casing between the clutch head and the shoulder 39, is a clutch releasing device, indicated as a whole by the numeral 49 and including the co-acting releasing members 50 and 51 which are best illustrated in Figs. 7 and 6, respectively. The member 50 includes a collar 52 which engages against the free end of the flange 38 of the clutch head and which, in turn, is provided with a flange or sleeve 53 which fits closely about the reduced portion of the valve casing and the free end of which is located adjacent the body proper of the clutch head. A helical spring 54 is located in the annular chamber formed between the flanges 38 and 53 and has its ends seated in sockets 55 formed in the opposed faces of the clutch head and releasing member 50. It will of course be clear that this spring 54 tends to hold the releasing member 50 and 130

clutch head in a predetermined angular position with respect to each other and to return such parts to that position if either one is moved out of it.

5 The co-acting clutch releasing member 51 includes a collar portion 56 which fits about the valve casing and engages against the adjacent face of the collar 52. This collar 56 is provided with an annular flange or sleeve 10 57 which engages, at its free end, against the shoulder 39 of the valve casing to provide an annular chamber about the valve casing to receive a helical spring 58, the ends of which seat in sockets 59 formed in the 15 valve casing and in the body proper of the releasing member 51. This spring performs the same function with respect to the releasing member 51 and valve casing that the spring 54 does with respect to the clutch 20 head and releasing member 50.

The releasing member 50 has formed at diametrically opposite sides of its otherwise plane surfaced inner end, reversely formed, peripherally extending cams 60 of less width 25 than the thickness of the walls of the clutch releasing members, whereby they may normally seat wholly within correspondingly located and shaped cam recesses 61 formed in the abutting end face and inner face of 30 the clutch releasing member 51. The releasing member 50 is provided interiorly with diametrically disposed, longitudinally extending keyways 62 which preferably, are in alinement with and extend into the cams 35 60 in order to give them added length and the valve casing is provided with keys 63 which seat in these keyways, the keys being so fitted in the keyways as to permit longitudinal movement of the clutch releasing 40 member 50 but to hold it against turning movement.

The keyways 48, previously mentioned, communicate at their inner ends with an annular recess 64, whereby the clutch head 45 34 may be turned in either direction without turning the valve stem, if it has previously been moved longitudinally of the valve stem toward the hand wheel a sufficient distance to position the outer ends of the keys 46 in 50 the chamber 64. It will therefore be clear that if the clutch releasing member 51 be turned in one direction, movement in the other direction, at all times, being prevented by the cams 60 and cam recesses 61, the co- 55 action between the cams and cam recesses will, inasmuch as the releasing member 50 is held against turning movement, force such releasing member toward the free end of the valve stem and therefore force the clutch head toward the hand wheel to disengage it 60 from the valve stem by bringing its keys 46 into the annular chamber 64 of the clutch head. The collar portion 56 of the releasing member 51 is provided with an upstanding 65 ing impact receiving shoulder or lug 65 by

means of which such member may be partially turned to accomplish the above releasing of the clutch head.

As previously mentioned, the above described valve is secured to a locomotive and a pipe 66 leads from the train pipe of the air brake system to the port 25 of the valve, while a pipe 67 leads from the port 24 of the valve into one end of a cylinder 68. This cylinder is mounted at any suitable 70 point upon the locomotive and is provided adjacent that end opposite the connection with the pipe 67 with a vent port 69. A piston 70 is mounted in the cylinder and capable, under train pipe pressure from the 75 valve 10 and pipe 67, of movement to a position past the vent port 69, whereby the train pipe may be vented through such port. This piston has a piston rod 71, the free end of which is connected to a link 72 having a 80 laterally directed terminal 73. A link 74 is slidably mounted in this terminal and provided with a head 75, whereby movement of the link 74 in one direction, will draw the piston 70 toward the pipe 67 and movement 85 in the opposite direction will have no effect upon the piston. This rod 74 or link is reciprocally mounted in a bearing 76 and at its free end is connected to another link 77 which, at its free end, is pivotally connected 90 at the point of pivotal connection of the toggle lever arms 78. One of these toggle lever arms is connected to the throttle valve 79 and the other to the handle 82 of a hand latch structure 80, the pawl of which is operated by a link 81 connecting it and the handle. The throttle valve lever is pivotally mounted at one end, as shown at 95 83 in the usual manner and connected intermediate its length with a link 84 leading to the 100 throttle valve, the pawl of the latch co-operating with a toothed segment 85 as is usual in such valve lever construction. The link 74, which is held against turning movement 105 because of its manner of connection with the link 77, is provided with a shoulder or lug 86 adapted, when the throttle valve lever is moved to closed position, to engage against the shoulder or lug 65 of the clutch releasing member to turn such member a 110 sufficient distance to free the clutch head 115 from the valve stem 28.

A cable 87 or other suitable flexible connection is secured at one end to the free end 120 of the lever 42, is passed downwardly about a pulley 88 and over a pulley 89 and connected at its opposite end to the upper end of a trip lever 90. This trip lever is pivotally mounted intermediate its length upon a bracket 92 supported at any suitable part 125 of the locomotive, preferably upon the cross head guides 93 and is provided at its lower end with a roller 94. The cable 87, immediately above the upper end of the lever 130 90, is passed between a pair of spaced pul-

leys 93 which serve as guides for the cable irrespective of in which direction the lever 90 may be swung. It will of course be apparent that swinging of the lever 90 in either direction will act through the cable to swing the lever 42 and therefore open the valve 22 unless the clutch head is released from the valve stem. This lever 90 is adapted to be swung through engagement with any suitable track obstacle, a preferred form of which is illustrated in Fig. 1. This obstacle includes a U-shaped body portion 96 which is pivotally mounted by its free ends in such a manner that it may be swung from horizontal to vertical position, the latter being the position shown, any suitable mechanism, not shown, being provided for this purpose. As this type of obstacle is fully illustrated in another patent granted to me on the 18th day of September, 1914, and bearing the No. 1,115,579, any further description of its construction and method of operation is believed to be unnecessary.

In operation, assuming that a locomotive equipped with my safety appliance passes in either direction, a track obstacle in raised or active position, the lever 90 will be swung through engagement of the roller 94 with the obstacle. This swinging of the lever, irrespective of the operation of such swinging, will act through the cable 87 to turn the clutch head 34 and therefore turn the valve 22 to open position providing the clutch head is locked to the valve stem as is normally the case. As soon as a train has moved a sufficient distance to free the lever 90 from the obstacle, the spring 54 of the valve structure will automatically return the clutch head to normal position, this being permitted, due to the inclined faces of the keys 46 and of the keyways 48, the valve still remaining open. Under these conditions, air will pass from the train pipe 66 through the valve 10 and pipe 67 into the cylinder 68, forcing the piston 70 toward the farther end of the cylinder. This movement of the piston acts through the links 71, 72 and 74 to release the hand latch of the throttle valve lever and swing the throttle valve lever to closed position. At the time that this lever reaches closed position, the piston 70 will have passed the vent port 69 and air will be vented from the train pipe to apply the air brakes of the train. It is of course true that the lug 86 is by the same movement brought into engagement with the impact receiving lug or shoulder 65 of the clutch releasing member 51, causing the forcing of the clutch head to inactive or released position. This, however, has no effect upon the valve, under these circumstances, and the valve can only be closed by manual manipulation of the hand wheel 31. It will of course be clear that the engineer may again open the throttle valve by the usual manipu-

lation of the throttle valve lever and that such opening of the throttle valve will release the clutch releasing member and thereby again lock the clutch to the valve stem. On the other hand, if the engineer sees a danger signal set and shuts the throttle valve lever before reaching the track obstacle, such movement of the lever will operate the clutch releasing member to free the clutch from the valve stem and swinging of the clutch head in the manner previously described will, under those circumstances, have no effect upon the valve which will remain closed. For this reason, if the engineer sees the danger signal in time and wishes to avoid an emergency application of the brakes, he can readily do so by closing the throttle valve to stop the train.

It should be noted that both the springs 27 and 36 tend to hold the frusto-conical plug valve 22 firmly to its seat and further that the spring 36 holds the clutch head in close engagement with the clutch releasing device 49 and returns the clutch head to normal position after opening of the throttle valve, and consequent release of the releasing member 51 of the clutch releasing device. The springs 54 and 58 tend to constantly maintain the members of the clutch releasing device and the clutch head in proper angular position with respect to each other.

Having thus described the invention, what is claimed as new is:

1. In a safety appliance for trains, the combination with a throttle valve and its lever and a train pipe, of a vent valve for the train pipe, a clutch head normally connected with the valve and forming an operating means therefor, track obstacle operated means for turning the clutch head to open the valve, and means for releasing the clutch head, whereby its turning will not open the valve.

2. In a safety appliance for trains, the combination with a throttle valve and its lever and a train pipe, of a vent valve for the train pipe, a clutch head normally connected with the valve and forming an operating means therefor, track obstacle operated means for turning the clutch head to open the valve, and means for releasing the clutch head, whereby its turning will not open the valve, said means operating upon closing of the throttle valve.

3. In a safety appliance for trains, the combination with a throttle valve, its lever and a train pipe, of a vent valve in the train pipe, means operable by opening of the vent valve for closing the throttle valve, a clutch head normally connected with the vent valve and longitudinally movable to free it of such connection, track obstacle operated means for turning the clutch head to open the vent valve, and means for moving the

- clutch head longitudinally to free it from connection with the vent valve, said means being operable by movement of the throttle lever to close the throttle valve.
5. In a safety appliance for trains, the combination with a throttle valve, its lever and a train pipe, of a vent valve in the train pipe, means operable by opening of the vent valve for closing the throttle valve, a clutch head normally connected with the vent valve and longitudinally movable to free it of such connection, track obstacle operated means for turning the clutch head to open the vent valve, and means for moving the clutch head longitudinally to free it from connection with the vent valve, said means being operable by movement of the throttle lever to close the throttle valve, and including co-acting cam members, one of which is movable upon swinging of the throttle valve lever to move the other and cause it to force the clutch head out of connection with the vent valve.
5. In a safety appliance for trains, the combination with a throttle valve, its lever and a train pipe, of a valve casing having ports communicating with train pipe sections, a turn plug valve mounted in the casing, a revoluble stem for the valve, a clutch head mounted upon the stem and movable longitudinally thereof, means co-acting between the stem and the clutch head to lock them for common turning movement in one position of the head on the stem and to leave the head free for independent turning movement when in another position on the stem, means normally holding the head in the former position, means operable by turning of the throttle valve lever to close the throttle valve for moving the head to the other position, and track obstacle operated means for turning the head irrespective of its position.
6. In a safety appliance for trains, the combination with a throttle valve, its lever and a train pipe, of a valve casing having ports communicating with train pipe sections, a turn plug valve mounted in the casing, a revoluble stem for the valve, a clutch head mounted upon the stem and movable longitudinally thereof, means co-acting between the stem and the clutch head to lock them for common turning movement in one position of the head on the stem and to leave the head free for independent turning movement when in another position on the stem, means normally holding the head in the former position, means operable by turning of the throttle valve lever to close the throttle valve for moving the head to the other position, and track obstacle operated means for turning the head irrespective of
- its position, said throttle lever operated means including a cam sleeve mounted on the valve casing for longitudinal movement 65 and engaging the clutch head, whereby the two move together, a second cam sleeve mounted on the valve casing for turning movement to move the first cam member longitudinally, and operative connection between the second sleeve and throttle valve lever.
7. In a safety appliance for trains, the combination with a train line, of a vent valve interposed in the train line including 75 a valve casing, a turn plug valve mounted in the casing and controlling venting of air therefrom, an operating head reciprocally mounted on the valve plug, keys carried by the valve plug to lockingly engage the head 80 in one position thereof, means for normally holding the head in such position, and a pair of co-acting cam sleeves mounted on the casing and operable to move the operating head to its other position. 85
8. In a safety appliance for trains, the combination with a train line, of a vent valve interposed in the train line including a valve casing, a turn plug valve mounted in the casing and controlling venting of air 90 therefrom, an operating head reciprocally mounted on the valve plug, keys carried by the valve plug to lockingly engage the head in one position thereof, means for normally holding the head in such position, a pair of 95 co-acting cam sleeves mounted on the casing and operable to move the operating head to its other position, and means normally holding the cam sleeves in inoperative position.
9. In a safety appliance for trains, the combination with a train line, of a vent valve interposed in the train line, including 100 a valve casing, a turn plug valve mounted in the casing and controlling venting of air therefrom, an operating head reciprocally mounted on the valve plug, keys carried by the valve plug to lockingly engage the head in one position thereof, means for normally holding the head in such position, a pair of 105 co-acting cam sleeves mounted on the casing and operable to move the operating head to its other position, and means normally holding the cam sleeves in inoperative position, 110 said means including helical springs surrounding the casing within the sleeves 115 with one end of each spring engaging its sleeve and the other end of each spring engaging the casing.

In testimony whereof I affix my signature in presence of two witnesses.
